UNITED STATES PATENT OFFICE.

JOHAN WALDEMAR LINDBERG, OF STOCKHOLM, SWEDEN.

DEVICE FOR SECURING KEYS IN LOCKS.

1,314,526.

Specification of Letters Patent.

Patented Sept. 2, 1919.

Application filed March 10, 1919. Serial No. 281,728.

To all whom it may concern:

Be it known that I, JOHAN WALDEMAR LINDBERG, a subject of the King of Sweden, residing at Stockholm, in the Kingdom of Sweden, have invented a new and useful Improvement in Devices for Securing Keys in Locks, of which the following is a specification.

The present invention refers to a device for securing keys in locks, and has for its purpose to provide a device which makes it impossible to open the door by means of a pick from the opposite side of the door. For the said purpose it has been proposed to use devices consisting of a stem to be introduced into the portion of the key-hole corresponding to the key-bit, and a member gripping the key between the key-handle and the lock, so that when the lock is bolted the key is prevented from being pushed out of the key-hole. Heretofore known devices of this kind, however, have the disadvantage of not being capable of preventing quite positively the breaking open of the door. There are key-holes of different widths, and the stem to be slipped into the key-hole can therefore not be made in such manner that it fills the key-hole completely in every case, consequently, said stem can not prevent the introduction of a pick through the key-hole. The old devices being so constructed that it is not quite impossible by means of a pick thus introduced to open the member gripping the key and to release it from engagement with the key, it will be understood that said old devices are not quite reliable.

The present invention has for its purpose to avoid the said disadvantage with the old devices. The invention is broadly characterized by this that the member gripping the key consists of a plate approximately perpendicular to the key-shank, a portion of said plate being made as a movable latch or the like capable of gripping around the key-shank and of being secured in such position of engagement by means of a stop device or catch arranged on the side of said plate directed from the key-hole. Said plate thus renders it impossible to reach the catch with a pick introduced through the key-hole, consequently it prevents an undue opening of the latch gripping the key.

An embodiment of the invention is illustrated in the accompanying drawing by way of example. Figure 1 shows a plan view of the device. Fig. 2 shows a front

view of the device when in use, and Fig. 3 shows a front view of the device with opened latch. Fig. 4 shows a side view of the device.

The device illustrated in the drawing consists of a stem 1 fitting into the key-hole below the shank of a key introduced into said hole. The rear portion of said stem has suitably a somewhat enlarged cross section, as shown in Fig. 1, in order better to fill out the key-hole and thus render it more difficult to introduce a burglar's tool, but the stem may have uniform cross section throughout its entire length. At the rear end of said stem 1 a plate 2 is secured perpendicularly to the stem, said plate supporting by means of a stud 3 a latch 4 forming in position of engagement as shown in Figs. 2 and 4, an upward continuation of the plate 2. When the lock has been bolted and the key turned in such manner that the key-bit and thus also the key-handle or bow are approximately horizontal, the stem 1 is introduced into the hole in the key-escutcheon 7 below the key, and afterward the latch 4 is swung down so that it grips around the shank of the key 5 back of the key-handle, that is to say, between said handle and the door, as shown in Figs. 2 and 4. It is now impossible to push out the stem 1 from the opposite side of the door, as the latch 4 will become forced against the handle of the key which is secured by the key-bit in the lock. Assuming that the key has been turned twice in the lock and that the stem 1 is sufficiently long to reach in under the portion of the key-shank where the key-bit is secured, it is even then not possible to open the lock from the outside of the door by turning the key by means of a burglar's tool, because even if the key was successfully turned so that the bolt of the lock was drawn back one step the key-bit would afterward strike against the stem 1 thus preventing further turning of the key.

In order to prevent any turning of the key and thus to make it impossible to open the lock by means of a pick even if the key had only been turned once, a second plate 6 is secured at approximately right angles to the plate 2. When the device has been introduced into the key-hole the said plate 6 will be approximately parallel to the key-handle. If it is attempted to turn the key from the outside, the key-handle will be

caused to bear against the plate 6 whereby its further turning will be prevented.

In the latch 4 there are cuts or notches 8 which will come exactly opposite the key-handle when the latch is swung down over the key-shank, as shown in Fig. 2. If it is now tried from the outside of the door to push the device out of the lock toward the inside of the door, the device will slide outward on the key which is held immovably in the lock, so that the said cuts or notches 8 will engage the two halves of the key-handle projecting to either side of the key-shank and thus provide a still more positive engagement between the device and the key. But for said notches 8 it would not be quite out of the question, by an attempt to push the device out of the key-hole from the outside of the door, if the edges of the key-handle adjacent the key-shank are not quite in alinement and perpendicular to the key-shank but form a more or less acute angle with one another, that the said edges would act as a wedge in the cut or opening 9 of the latch and thus raise the latch. If the device is used for a key-hole which is so large that it is not quite filled out by the stem 1, but there being a clearance between said stem and one wall of the key-hole, there would be a possibility of reaching the latch 4 and to raise it by means of a burglar's tool from the outside of the door, in which case the device could be detached from the key and pushed out of the key-hole. In order to provide against such possibility a catch 12 is pivoted on a stud 11 on the side of the plate 2 directed from the key-hole, said catch being maintained by a spring 13 bearing against the bent edge 14 of the plate 2 in such normal position as to project into the path of turning of a portion of the latch 4 and thus in such position to prevent the turning of the latch 4, as will be understood from Fig. 2. The catch 12 is provided with a projecting lug 15 by means of which the catch 12 may be turned in such manner that its end projecting into the said path of movement of said latch 4 will be moved out of said path of movement, as shown in Fig. 3, after which it is possible to turn the latch 4 on the stud 3, so that the device may be detached from the key and pulled out of the key-hole, or introduced into the same. When the device

has been introduced and the latch 4 has 55 been turned down so as to engage the key, the catch 12 will automatically be moved by the spring 13 into such position as to secure the latch 4. The plate formed by the members 2 and 4 now lies between the 60 key-hole and the catch 12, thus making it impossible to reach the catch by means of a pick introduced through the key-hole.

It will be understood that the invention is not limited to the embodiment illustrated 65 in the drawing, as various changes and modifications may be made therein without departing from the spirit of the invention as defined in the appended claims.

I claim:

1. In a device for securing keys in locks, the combination of a stem adapted to be introduced into a key-hole, a plate secured approximately perpendicularly to said stem, a latch attached to said plate so as to be movable in a plane approximately perpendicular to said stem and adapted to grip around the shank of a key, and means on the side of said plate opposite said stem for securing said latch in operative position. 70

2. In a device for securing keys in locks, the combination of a stem adapted to be introduced into a key-hole, a plate secured approximately perpendicularly to said stem, a latch attached to said plate so as to be movable in a plane approximately perpendicular to said stem and adapted to grip around the shank of a key, said latch being provided with notches in such manner that in operative position of the latch said notches are 75 located opposite the handle of the key when turned 90° in the lock, and means on the side of said plate opposite said stem for securing said latch in operative position. 80

3. In a device for securing keys in locks, 85 the combination of a stem adapted to be introduced into a key-hole, a plate secured approximately perpendicularly to said stem, a latch attached to said plate so as to be movable in a plane approximately perpendicular to said stem and adapted to grip around the shank of a key, a catch pivoted to the side of said plate opposite said stem and adapted to engage so as to secure said latch in operative position, and a spring actuating said 90 catch to move the same into position in engagement with said latch. 95

JOHAN WALDEMAR LINDBERG.
